HANDLE FOR A GRASS SHEAR

Dieter Raffler and Franco Clivio, Ulm, Germany,
assignors to Gardena Kress & Kettner GmbH

Filed Apr. 3, 1974, Ser. No. 457,713

Claims priority, application Germany Oct. 4, 1973

Term of patent 14 years

Int. Cl. D6—03

U.S. Cl. D6—8

Fig. 1

FIG. 1 is a side view of a handle for a grass shear or similar article showing our new design, the broken lines representing the extension handle of a grass shear or similar article being shown for illustrative purposes only;

FIG. 2 is an enlarged view of FIG. 1;

FIG. 3 is a perspective view of the handle shown in FIG. 1;

FIG. 4 is a front elevational view thereof;

FIG. 5 is a top elevational view thereof; and

FIG. 6 is a rear elevational view thereof.

We claim:

The ornamental design for a handle for a grass shear, as shown.
